US00D925115S

(12) **United States Design Patent** (10) **Patent No.:** **US D925,115 S**
(45) **Date of Patent:** **** Jul. 13, 2021**

(54) **POWER SUPPLY DEVICE FOR ELECTRONIC CIGARETTE**

(71) Applicant: **Shenzhen Smoore Technology Limited**, Guandong (CN)

(72) Inventor: **Jianliang Wang**, Guandong (CN)

(73) Assignee: **SHENZHEN SMOORE TECHNOLOGY LIMITED**, Shenzhen (CN)

(**) Term: **15 Years**

(21) Appl. No.: **29/749,912**

(22) Filed: **Sep. 10, 2020**

Related U.S. Application Data

(63) Continuation of application No. 29/682,369, filed on Mar. 5, 2019, now Pat. No. Des. 900,385.

CLAIM

The ornamental design for a power supply device for electronic cigarette, as shown and described.

DESCRIPTION

FIG. 1 is a perspective view of a power supply device for electronic cigarette showing my design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is an enlarged top plan view thereof; and,

FIG. 7 is an enlarged bottom plan view thereof.

The dash-dash lines in the drawings depict portions of the power supply device for electronic cigarette, the portions forming no part of the claimed design.

1 Claim, 7 Drawing Sheets
